Patented Sept. 12, 1922.

UNITED STATES PATENT OFFICE.

ALBERT M. GUILLET, OF CHARLOTTE, NORTH CAROLINA.

GAUGE.

Application filed February 26, 1920. Serial No. 361,542.

To all whom it may concern:

Be it known that I, ALBERT M. GUILLET, a citizen of the United States, residing at Charlotte, in the county of Mecklenburg and

5 State of North Carolina, have invented certain new and useful Improvements in Gauges, of which the following is a specification, reference being had to the accompanying drawings.

10 This invention relates to certain improvements in gauges and has relation more particularly to a device of this general character especially designed and adapted for use in detecting portions of a spindle which are out of alignment, and it is an object of the invention to provide a novel and improved device of this general character embodying means whereby a spindle may be effectively tested to determine the condition thereof and

20 to facilitate the straightening of the spindle.

Another object of the invention is to provide a novel and improved device of this general character including a suitably supported table provided with means whereby

25 a spindle may be rotatably supported thereby, together with means supported by the table for coaction with the spindle to determine or locate portions of the spindle which are out of alignment.

30 Furthermore, it is an object of the invention to provide a novel and improved device of this general character including means for supporting a spindle whereby the same may be readily rotated manually, together with means whereby the spindle may be supported for rotation at a relatively high speed so that said spindle may be subjected to a visual test.

The invention consists in the details of 40 construction and in the combination and arrangement of the several parts of my improved gauge whereby certain important advantages are attained and the device rendered simpler, less expensive and otherwise 45 more convenient and advantageous for use, as will be hereinafter more fully set forth.

The novel features of my invention will hereinafter be definitely claimed.

In order that my invention may be the 50 better understood, I will now proceed to describe the same with reference to the accompanying drawings, wherein:

Figure 1 is a view in perspective, illustrating a gauge constructed in accordance 55 with an embodiment of my invention;

Figure 2 is a fragmentary view in per-

spective of the outer end portion of a bearing comprised in the carriage, as herein embodied;

Figure 3 is a view in top plan of the table 60 as disclosed in Figure 1;

Figure 4 is a fragmentary view partly in side elevation and partly in longitudinal section of the device as herein embodied;

Figure 5 is a sectional view taken sub- 65 substantially on the line 5—5 of Figure 3;

Figure 6 is a fragmentary view partly in section and partly in elevation illustrating the means for positively driving the spindle;

Figure 7 is a view in top plan, illustrating 70 a table constructed in accordance with a further embodiment of my invention;

Figure 8 is a fragmentary view partly in side elevation and partly in section of the structure illustrated in Figure 7; 75

Figure 9 is a transverse sectional view, illustrating the mounting and construction of one of the keys as embodied in the form of invention illustrated in Figures 7 and 8; and

80 Figure 10 is an enlarged fragmentary view partly in section and partly in elevation showing the whirl or base portion of a spindle and the co-acting bearing arm.

As disclosed in the accompanying drawings, A denotes an anvil of desired dimensions and configuration and which is anchored to the upper end portion of the stand C by set screw 1, or the like. The lower portion of the stand C is provided with a flange F adapted to be secured to a floor or other support. Coacting with the stand C are the braces B herein disclosed as three in number and which braces are also adapted to have their lower end portions suitably secured to the floor or other support. 95

Carried by one end portion of the anvil A is an outwardly disposed arm 2 terminating in a depending extension or part 3. Bolted or otherwise detachably engaged with the depending part or extension 3 is a lower end portion of an upstanding arm 4. The arm 4 depends from an elongated table T disposed longitudinally on a predetermined incline with respect to the horizontal, said 105 inclination of the table T serving to materially facilitate the use of the device. The lower end portion of the table T is provided with the longitudinally disposed slot 5 through which extend the clamping members 6. The clamping members 6 also extend 110 through a longitudinally disposed slot 7, pro-

vided in the carriage 8 mounted upon the table T and whereby said carriage 8 may be effectively locked in desired adjusted position longitudinally of the table T. The inner end portion of the carriage 8 is provided with a pair of upstanding brackets or plates 9 and 10 each of which is provided with a vertically disposed slot 11. Extending through the slot 11 of the plate 9 are the 10 clamping screws 12 which coact with the block 14 provided in its upper edge portion or margin with a V-shape notch 15. This block or bearing 14 may be readily adjusted toward or from the table T in accordance 15 with the requirements of practice and effectively maintained through the instrumentality of the screws 12.

Disposed through the slot 11 in the bracket or plate 10 are the binding screws 16 which 20 coact with the block or bearing 17 which is also adjustable toward or from the table T and held in its desired adjusted position through the medium of the screws 16. The upper edge portion or margin of the bearing 25 or block 17 is provided with a U-shaped channel 18 which is in direct longitudinal alignment with the notch 15. The channel 18 is defined by an outwardly extending bearing arm 19, U-shaped in cross 30 section, and which has its outer or free end provided with a removable cap or head 20, detachably held in applied position by the screws 21, or the like. The cap or head 20 is made removable so that the 35 same can be readily replaced when the occasions of practice may so necessitate and particularly when the same has become unduly worn. The upper end of the plate or head 20 is provided with the V-shape notch 40 22 which is in direct alignment with the notch 15 and channel 18, hereinbefore referred to.

The upper end portion of the table T or 45 that end portion remote from the carriage 8 is provided with a transversely disposed slot 23 through which is disposed a threaded shank 24 depending from an upstanding post 25, and coacting with the shank 24 is a clamping nut 26 whereby the post 25 may 50 be readily adjusted in a direction transverse of the table T and effectively maintained in its desired adjusted position. The upper portion of the post 25 is provided with an enlargement or head 27 through which is 55 slidably disposed a spindle center 28. The center 28 is adjustable longitudinally on the post or stud 25 and is held in desired adjusted position by the binding screw 29 in threaded engagement with the head or enlargement 27 and engageable with the 60 center 28. In practice, the notches 15 and 22 and channel 18 must be in alignment and also in alignment with the working end or point of the spindle 28 and in order to obtain 65 this arrangement, it is of utmost im-

portance to provide the upper face of the table T with the guide marks 30 so that it may be readily determined the degree or extent to which the spindle is out of alignment. The upper portion of the table T 70 and at the side thereof adjacent to the anvil A is provided with an upstanding flange 31 with the upper marginal portion of which is integrally formed a laterally extending supplemental table S. E denotes a straight 75 edge having a marginal portion imposed upon the table S and the opposite end portions of said straight edge are provided with the outstanding arms 32. The straight edge E serves as a rest or support for the 80 digit of a hand, preferably the thumb, of an operator for a purpose to be hereinafter more particularly referred to. Each of the arms 32 adjacent its junction with the straight edge E is provided with a slot 33 85 through which is directed a binding screw 34 also disposed through the adjacent end portion of the table S. By this arrangement, the straight edge may be laterally adjusted in accordance with the requirements of 90 practice and particularly with respect to the spindle with which said straight edge coacts. The opposite end portions of the supplemental table S inwardly of but in close proximity to the arms 32 are provided 95 with the graduations or indicating marks 35 whereby the requisite adjustment of the straight edge may be effected in accordance with the requirements of practice. The working margin of the straight edge is 100 adapted to be disposed on the incline in conformity with the taper of the spindle.

To further facilitate the desired adjusting movement of the straight edge E, the outer extremities of the arms 32 are provided with the depending wings or lugs 36 through each of which is disposed a shank 37 in threaded engagement with a lug or wing 38 depending from the supplemental table S. The outer end of the shank 37 is 110 provided with an operating head 39 which engages the outer face of the coacting wing or lug 36. The lug 36 is constantly urged toward said head 39 by an expandible member 40, herein disclosed as a coil spring 115 encircling the shank 37 and interposed between the lugs or wings 36 and 38. In practice, the operator, preferably sitting in front of the device, places the spindle Y, after first 120 coating the same with lamp black or other kindred adhesive powder, with the whirl or base end portion engaged within the notches 15 and 22 with the top of the spindle Y 125 pointing closely to the point or working end of the spindle center 28 and which center, as hereinbefore stated, must be adjusted into perfect alignment with said bearing notches 15 and 22. The straight edge E is then adjusted with respect to the applied spindle Y at proper distance there- 130

from and in conformity to the taper of the spindle. The spindle Y is then manually rotated and while performing this operation, the operator places a digit of a hand, 5 preferably the thumb, upon the outer edge of the straight edge E adjacent to the applied spindle Y and in such a manner that as the spindle Y is rotated, the thumb or other digit of the operator marks or indicates the uneven portions of the spindle 10 Y by scraping off the lamp black or the like therefrom. These marks are immediately used by the operator in straightening out the spindle upon the anvil A and preferably 15 with a composition hammer of soft material. After repeating the foregoing operation several times and until the operator believes he has sufficiently straightened the spindle Y, he removes all of the lamp black 20 or the like from the spindle and subjects said spindle to a visual test and during which test, the spindle Y is rotated at a relatively high rate of speed.

The end portion of the anvil A remote 25 from the arm 2 is provided with an outstanding plate or arm 41. Engaged with the arm 41 is a spindle base and bolster 42, the lower portion of which being disposed through a suitable opening 43 in the plate 41 and with 30 the lower portion of which coacts a clamping nut 44. The spindle Y is rotatably engaged with said base and bolster 42 when subjected to the visual test.

Depending from a side margin of the arm 35 or plate 41 is a plate or flange 45. Hingedly connected, as at 46, with the lower marginal portion of the plate or flange 45 is the lower marginal portion of a plate 47 adapted to be moved in a direction toward or from the 40 plate or flange 45. In order to effect this movement of the plate 47, the same is provided at a suitable point along a side thereof with an outstanding lever 48. The lever 48 is provided with an inwardly directed finger or rod 49 terminating in a laterally disposed extension or lug 50 which overlies the face of the plate or flange 45 and with 45 which said lug or extension 50 contacts to limit the extent of movement of the plate 50 47 away from the plate or flange 45.

Suitably secured to the outer side face of the plate 47 is a motor M, preferably electric, and which has its rotating armature revolving about a vertically disposed axis. 55 Operatively engaged with the armature of the motor is a friction wheel 51, adapted to engage the whirl of the spindle when said spindle is applied to the base or bolster 42, said friction wheel being of such diameter 60 with respect to the whirl of the spindle to cause said spindle to rotate at a relatively high speed. With the spindle applied to said base and bolster 42 and rotating through the instrumentality of the wheel 51, the 65 operator can further determine or test the

spindle for its accuracy and smoothness by visual inspection and also by the application of his fingers to the spindle.

Normally the plate 47 is at its limited movement away from the flange or plate 45 70 so that the wheel 51 will be free of the whirl of the spindle when first applied to the base and bolster 42. The weight of the motor M and the parts carried thereby serves to maintain this normal position of the plate 47. 75 When it is desired to rotate a spindle applied to the base and bolster 42, the operator engages the lever 48 and swings the plate 47 in a direction toward the plate or flange 45 sufficiently to cause the wheel 51 to engage 80 the whirl of the spindle. By this means, it will at once be obvious that the rotation of a spindle when applied to the base and bolster 42 is at the will of the operator.

In the straightening of spindles used in 85 connection with the manufacture of finer yarns, it is essential that the smaller or finer uneven or crooked features of the spindles be determined with extreme accuracy and for such purposes, I find it of importance to 90 employ the arrangement or construction particularly illustrated in Figures 7 to 9. When this latter arrangement or construction is employed, the straight edge E and the parts for adjusting it are removed from the 95 supplemental table S and the elongated rods R and R' mounted upon said table. The opposite end portions of the rod R are provided with lateral extensions 52 which are directed through the slots 53 in the opposite 100 end portions of the table S with the rod R substantially in contact with the table S throughout its length. Engaged with the extensions 52 are the clamping nuts 54 co-acting with the under face of the table S and 105 whereby the rod R may be maintained in desired lateral adjustment as may be occasioned by the taper of the spindle and which adjustment is facilitated by the graduations or marks 35, hereinbefore referred to. 110 The rod R' is also provided at its opposite end portions with the laterally extending fingers or extensions 55 disposed through the additional slots 56 in the table S and which rod R' is clamped in the desired adjustment 115 through the medium of the nuts 57. As is clearly illustrated in the accompanying drawings, it is to be noted that the rod R', when applied, is positioned above and spaced from the table T and the rod R. 120

Slidably mounted upon the rod R' is a plurality of carriers or supports K for the fingers. Each of the carriers or supports K comprises a flat elongated body portion 58 having its longitudinal marginal portions 125 provided with depending side flanges or wings 59. The flanges or wings 59 are provided with the transversely aligned openings 60 through which the rod R' is loosely directed so that the carrier or support K may 130

be readily moved or adjusted longitudinally of said rod. The outer or rear edges of the flanges or wings 59 are substantially perpendicularly related to the body portion 58 and the free longitudinal edges of said wings or flanges 59. These rear edges *a* have contact with the rod R whereby the proper mounting of carrier or support in working position is assured. In order to accomplish this 10 action, it is to be understood that the rod R' is positioned inwardly of the rod R.

The outer or working extremity of the body portion 58 of the carrier or support K has disposed therethrough a binding screw 15 61 which is also directed through a longitudinally disposed slot provided in the rear end portion of a flat finger 62 partially underlying the forward part of the body portion 58. By this means, the finger 62 may 20 be longitudinally adjusted with respect to the spindle as the occasions of practice may necessitate.

The fingers 62 of the carriers or supports K, in practice, take the place of the digit 25 of the operator and also supplant the use of the straight edge E. After the fingers 62 have been properly adjusted with respect to the carriers or supports K, the spindle after being applied, as hereinbefore stated, 30 is manually rotated and the outer or working end of the spindle scrapes the lamp black or the like from the spindle to mark or indicate the portions of the spindle to be straightened. It is also to be understood 35 that the carriers or supports K may be adjusted to the requisite positions longitudinally of the spindle at will of the operator.

From the foregoing description, it is thought to be obvious that a gauge 40 constructed in accordance with my invention is particularly well adapted for use by reason of the convenience and facility with which it may be assembled and operated, and it will also be obvious that my invention is 45 susceptible of some change and modification without departing from the principles and spirit thereof, and for this reason I do not wish to be understood as limiting myself to the precise arrangement and formation of the several parts herein shown in carrying out my invention in practice except 50 as hereinafter claimed.

I claim:—

1. A device of the class described comprising a support, a table carried thereby, 55 an elongated support for the whirl end of a spindle carried by said table, and a spindle center carried by the table, said spindle center having its longitudinal axis disposed in alinement with the longitudinal axis of said support.

2. A device of the class described comprising a support, a table carried thereby, 65 an elongated support for the whirl end of a spindle carried by said table, and a spindle center carried by the table, said spindle center being longitudinally adjustable, and having its longitudinal axis disposed in alinement with the longitudinal axis of said support.

3. A device of the class described comprising a support, a table carried thereby, an elongated support for the whirl end of a spindle carried by said table, and a spindle center carried by the table and having its 75 longitudinal axis disposed in alinement with the longitudinal axis of said support, said spindle center being adjustable in a direction transverse to the longitudinal axis of said center.

4. A device of the character described comprising a supporting member, a table, spindle bearings carried by the table, a supplemental table carried by the first named table, finger supports mounted upon the supplemental table, and adjustable fingers carried by the supports.

5. A device of the character described comprising a supporting member, a table, 90 spindle bearings carried by the table, a supplemental table carried by the first named table, finger supports mounted upon the supplemental table, and adjustable fingers carried by the supports, said supports being independently adjustable one toward the other.

6. A device of the character described comprising a table, spindle bearings carried thereby, a supplemental table carried by the first named table, a transversely adjustable 100 rod carried by the supplemental table, and gauge fingers mounted upon said rod.

In testimony whereof I hereunto affix my signature.

ALBERT M. GUILLET.
